COFFERDAM FRAME

Stephen A. Healy, Chicago, Ill., and Jesse J. McShane and Nels Carr, Davenport, Iowa; said McShane and said Carr assignors to said Healy

Application September 24, 1932, Serial No. 634,636

3 Claims. (Cl. 61—34)

The present invention pertains to a frame for supporting the planking of a cofferdam for use in connection with construction operations in rivers, lakes, and the like. Among the objects of this invention are to provide means enabling the rapid construction of a cofferdam; to provide means rendering it possible to build a supporting structure outside of the water, as on a barge, and then place the structure in the water in position to have the planking applied thereto, thus completing the supporting means for the earth, rocks, and the like, used in the cofferdam; to provide improved mechanism for the purpose indicated; to provide an apparatus of the character indicated which can be fabricated in units, which units can be assembled end to end during the fabrication of the cofferdam; to provide a rigid structure of the character indicated; and such further objects, advantages and capabilities as will hereafter appear and as are inherent in the construction disclosed herein. Our invention further resides in the combination, construction and arrangement of parts illustrated in the accompanying drawings and, while we have shown in the annexed drawings what we consider the preferred embodiment of this invention, we desire the same to be understood as illustrative only and not to be interpreted in a limiting sense.

In the drawings annexed hereto and forming a part hereof,

Fig. 1 is a plan view of one structural unit of a cofferdam embodying our invention;

Fig. 2 is a fragmentary elevation, partly broken away, showing an external view of a partly completed structure in accordance with our invention;

Fig. 3 is a transverse section taken substantially along the plane indicated by the line 3—3, Fig. 1;

Fig. 4 is a detailed cross section showing the means for connecting two units of a cofferdam together;

Fig. 5 is a fragmentary section to show in greater detail a part of the present construction.

Reference will now be made in greater detail to the annexed drawings for a more detailed explanation of the present invention. In this connection reference will first be made to Fig. 3 showing a unit of our construction partly in elevation and partly in section. This comprises a plurality of substantially upright posts 1 preferably made from sections of I-beams. These posts are connected by cross tie members 2 of similar form, connected at their ends to an edge

of each of a pair of posts 1. We have shown these as being connected by means of angles 3 fastened in place by means of bolts or rivets 4. Secured adjacent the ends of the cross ties 2 are angles 5 which are perforated for the diagonal brace rods 6. It will be seen that this gives a very rigid frame unit for the support of the planking 7 forming the side walls of the cofferdam.

Longitudinal I-beams 8 are secured to the outer faces of the posts 1 and thus secure together a plurality of the frames described above. These longitudinal beams 8 serve as an outer support against which the planking 7 rests and against which it is forced by the wedges 9 which are driven in between the planking and other I-beams 10 which pass through openings 11 in the webs of the posts 1. This construction is shown most clearly in Fig. 5. From the foregoing it will be seen that there is formed a very rigid framework into which the planks may be placed and in which they may be tightly secured by driving in the wedges 9.

As shown in Fig. 2, a plurality of units, such as shown in Figs. 1 and 3, are connected end to end to form a continuous support for the planking and there is thus formed an elongated box into which earth, sand, gravel, and the like, may be dumped to prevent or substantially prevent water from passing through the cofferdam. The means for connecting the frames to each other is shown in Figs. 1, 2 and 4, from which it will be seen that I-beams 12 are secured to an end of each of the longitudinal beams 8. Any suitable means for attaching these I-beams may be used but we have found the angles 13 very suitable for this purpose. Bolts 14 pass through these angles and the webs of the beams 8 and, since the I-beams 12 are secured to the angles 13, this results in securing the beams 8 and 12 together.

The ends of the beams 8 which are adjacent the beams 12 have similar angles 13a attached thereto by means 14 and to these angles are attached channels 15 of peculiar formation, as will be evident from Fig. 4. The channel 16 of member 15 and one flange of I-beam 12 are connected by sliding the two together, as shown in Fig. 4. From Fig. 2 it will be apparent that the two frameworks may be at different elevations without in any way interfering with the operation thereof. The planks 7 are put in place and driven down, generally as far as they will go, two layers thereof being used and the joints being out of alignment, as indicated in Fig. 1. Wedges 9 are driven in to force the planks together and
